NELSON H. RAYMOND, OF BUFFALO, NEW YORK, ASSIGNOR TO CLIFTON MANUFACTURING COMPANY, OF JAMAICA PLAIN, MASSACHUSETTS, A CORPORATION OF NEW JERSEY.

METHOD OF CLEANING PIPES.

1,194,542.

Specification of Letters Patent.

Patented Aug. 15, 1916.

Application filed December 5, 1911. Serial No. 684,076.

To all whom it may concern:

Be it known that I, NELSON H. RAYMOND, a citizen of the United States, residing at Buffalo, in the county of Erie and State of New York, have invented new and useful Improvements in Methods of Cleaning Pipes, of which the following is a specification.

This invention relates to a method for 10 cleaning metallic pipes or tubes which are more particularly designed for use as electrical conduits.

In the manufacture of such pipes and particularly those made from iron, more or less 15 scale, grease and other deleterious matter adheres to the inner and outer surfaces of the same and it therefore becomes necessary to clean these pipes before applying thereto a protective coating by galvanizing or 20 enameling. Heretofore the scale, grease and other deleterious material has been removed from the pipes preparatory to applying the protecting coating thereto by immersing the pipes in a pickling solution consisting, for 25 instance, of a mixture of sulfuric and hydrochloric acid. Owing to the fact that the scale is usually thicker on the inner side of the pipe than on the outer side and for the further reason that the inner side of the 30 pipe usually contains more or less silica scale while the outer side is comparatively free from silica scale and instead thereof has a light mill scale, an acid treatment of the pipes as heretofore practised is objectionable because the outer side of the pipes 35 is acted upon excessively by the time the acid has removed the scale, grease and dirt on the inner side of the pipe. This results in pitting the exterior of the pipes so that 40 they look bad and cannot be covered uniformly with enamel or other protective coating. Furthermore, when the pipe has been previously threaded on its exterior this prior method of cleaning the same also results in partly eating such threads and rendering it impossible to make a perfect screw 45 joint between the several sections of a conduit.

It is the object of this invention to provide 50 a method whereby the interior of such pipes may be effectively and thoroughly cleaned of scale, grease, dirt and other deleterious material without injuriously affecting the exterior of such pipes.

In practising my invention a cutting or 55 cleaning solution consisting, for instance, of a mixture of sulfuric acid and hydrochloric acid is propelled through the interior of each pipe which solution as it escapes from one end of the pipe may be again introduced 60 into the opposite end and thus keep the solution constantly in circulation. By this means the solution is maintained in a thoroughly mixed condition, any bubbles formed on the interior of the pipe are 65 bursted, and new solution is constantly supplied, so that all parts of the internally grease and scale coated surface of the pipe are attacked by the solution and thoroughly cleaned. After the pipe has been thus 70 cleaned on its interior a neutralizing solution is propelled through the same for the purpose of killing the traces of acid which are deposited on the interior of the pipe and arresting the cutting action of the same. 75 This neutralizing solution may contain lime, soda, lye or any other alkali or caustic and the same is also preferably circulated through the pipe by taking the solution which escapes from one end of the pipe and 80 reintroducing the same at the other end of the pipe. After the effect of the acid treatment on the interior of the pipe has been thus neutralized this surface of the pipe is 85 washed out so as to remove therefrom the traces of cutting and neutralizing solutions, this being preferably effected by circulating water through the pipe in the same manner in which the cleaning or cutting and the neutralizing solutions were circulated 90 through the pipe.

The outer side of the pipe may be cleaned in any suitable way, for instance, by passing the same through a pair of scratch rolls which mechanically remove the dirt and 95 scale adhering thereto and the same may also be cleaned chemically by immersing the same for a suitable period in an acid cleaning solution at which time this solution may also enter the interior of the pipe and further clean the bore of the same. Any traces of acid adhering to the inner and outer side of the pipe may be neutralized by immersing the same in a caustic solution and then immersing the same in water. After the 100 pipe has been thus cleaned on its interior and exterior surfaces the same may be provided with a protective coating both inter-

nally and externally in any suitable manner, for instance by immersing the same in a bath of the desired kind of protective coating.

5 Various means may be employed for carrying my improved method of cleaning pipes into effect, that shown in the accompanying drawing being suitable and constructed as follows:

- 10 1 represents an upright manifold or distributing chamber which is provided on one of its upright walls with a plurality of laterally projecting discharge nozzles 2. This distributing chamber may be supplied 15 at different times either with a cutting medium or solution such as sulfuric and hydrochloric acid, a neutralizing medium or solution such as lye, and a washing medium such as water. As shown in the drawings, 20 the cutting solution is contained in a tank or reservoir 3 from which it is supplied to the upper part of the distributing chamber by means of a pipe 4 containing a valve 5 whereby the delivery of the cutting solution 25 to the distributing chamber may be controlled. A similar tank or reservoir 6 adapted to contain a quantity of neutralizing solution is also connected with the upper end of a distributing chamber by means of 30 a pipe 7 containing a valve 8 whereby the supply of neutralizing solution from the tank or reservoir 6 to the distributing chamber may be controlled.

Near its upper end the washing medium 35 or liquid may be supplied to the tank by means of a pipe 9 containing a valve 10 whereby the supply of washing medium may be controlled.

Each of the delivery nozzles of the 40 distributing chamber is inserted into the front or receiving end of one of the pipes or tubes 11 which are to be cleaned, these pipes being preferably supported in a position in which they incline from their receiving toward 45 their delivery ends by resting the same on a rack 12, as shown in the drawings, or by any other suitable means. Adjacent to the outlet ends of the pipes to be cleaned is arranged a receiving pan or catch basin 13 50 which is provided in its upper part with a screen 14.

15 represents a pump of any suitable construction which has its inlet connected by a pipe 16 with the lower part of the catch pan 55 or basin while its outlet end is connected with a main return pipe 17. The latter is provided with two branch pipes 18, 19 leading respectively to the upper ends of the cutting solution tank and the neutralizing solution tank, these branch pipes being provided, respectively, with valves 20, 21 for the purpose of controlling communication between these tanks and the return pipe of the pump. The return pipe of the pump is 60 also provided with a branch pipe 22 which

contains a valve 23 whereby the discharge from the pump may be run to a sewer or other waste place.

In practising my improved method for cleaning pipes a plurality of such pipes are 70 supported upon the rack and slipped at their front or receiving ends over the discharge nozzles of the distributing chamber and the valves 8, 10, 21, 23 are closed, while the valves 5 and 20 are opened, thereby cutting 75 off the supply of wash water and the neutralizing solution and also closing the waste outlet of the pump but placing the cutting solution tank in communication with the distributing chamber. In this position of the 80 valves the cutting solution flows from the cutting tank into the distributing chamber and from the latter outwardly through the several discharge nozzles and into the front ends of the several pipes. The cutting solution then flows solely by gravity through the several pipes from the inlet to the outlet ends thereof and during this passage the cutting solution removes scale, grease and other deleterious material from the interior of the 85 pipes. As the cutting solution escapes from the rear or tail ends of the several pipes it drops into the catch basin or pan, any solid impurities contained therein being separated therefrom by means of the screen 90 while the clear liquid gathers in the lower part of the pan. While the cutting solution is thus flowing through the pipes under treatment and escapes into the catch basin the pump is in operation and carries the cutting solution from the lower part of the catch basin back into the cutting solution reservoir or tank from whence it flows again 100 into the distributing chamber and through the pipe under treatment as before described. 105 In this manner the cutting solution is constantly kept in circulation through the pipes to be cleaned, whereby any bubbles formed on the pipes are broken, the solution is constantly agitated, and new or active parts of 110 this solution having a cutting capacity are brought into contact with all parts of the interior of the pipes and a thorough cleaning of the pipes is insured. After this cutting solution has been circulated in this 115 manner a sufficient length of time to thoroughly clean the pipes, which time may be determined from experience and also by noting the condition of the pipes preparatory to cleaning the same, the cutting solution tank is cut off by closing the valves 5 and 20, it being understood that all of the cutting solution is first returned to the tank 3, by means of the pump before the valve 20 is closed.

120 After the treatment of the pipes by the cutting solution has been accomplished the valves 8 and 21 of the neutralizing tank are opened and the solution of this tank is permitted to flow into the distributing chamber, 130

thence to the several tubes to be cleaned, thence into the catch basin and then returned by the pump to the neutralizing solution tank from whence it is again returned to the 5 distributing chamber and again circulated through the pipes under treatment as long as necessary to thoroughly neutralize all traces of the acid which are left in the pipes after the cutting treatment. After this neutralizing treatment the valve 8 is closed so as to cut off the further supply of neutralizing solution to the distributing chamber and after the pump has returned to the neutralizing tank all the neutralizing solution in the 10 distributing tank or chamber, tubes 11 and catch basin, then the valve 21 of this tank is also closed. The valve of the water supply pipe 10 and the valve 23 of the waste pipe are now opened, thereby causing water to flow 15 into the distributing chamber and through the several pipes under treatment and into the catch basin, from which latter the water is taken by the pump and discharged through the waste pipe 22 to a sewer or other 20 receptacle provided for this purpose.

My improved process for cleaning pipes

permits this operation to be effected economically and expeditiously and leaves the pipes in a condition in which they are free from pits or similar defects, and enables the 30 same to be enameled uniformly and present a finished and even appearance.

I claim as my invention:

1. The herein described method of cleaning tubes which comprises passing a cutting 35 solution through the tube, and then passing a neutralizing solution through the tube, said solutions being returned from the outlet to the inlet of said tube.

2. The herein described method of cleaning tubes which comprises passing a cutting solution through the tube, then passing a neutralizing solution through the tube, and then passing a washing medium through the 40 tube, said solutions being returned from the 45 outlet to the inlet of said tube.

Witness my hand this 1st day of December, 1911.

NELSON H. RAYMOND.
